UNITED STATES PATENT OFFICE.

EDWIN W. BULLARD, OF SPRINGFIELD, MASSACHUSETTS.

SCREW-CUTTING DEVICE.

SPECIFICATION forming part of Letters Patent No. 737,204, dated August 25, 1903.

Application filed May 19, 1903. Serial No. 157,847. (No model.)

To all whom it may concern:

Be it known that I, EDWIN W. BULLARD, a citizen of the United States, residing at Springfield, in the county of Hampden and State of Massachusetts, have invented new and useful Improvements in Screw-Cutting Devices, of which the following is a specification.

This invention relates to screw-cutting devices, and particularly to improvements in tools of this class in which the dies are constructed to open automatically when the screw has been threaded, thereby obviating the necessity of reversing the rotation of the tool or the work to withdraw the latter.

15 The particular object of this invention is to provide improved means to effect the opening and closing of the dies and to improvements in the construction of the device, whereby it is adapted to be operated either by the 20 endwise movement of the tool, as in a certain type of screw-machines, or by the rotative movement of a screw-machine turret in which the tool is securely fixed, all as hereinafter fully described in the following specification and pointed out in the claims forming part 25 thereof.

In the drawings forming part of this specification, Figure 1 is a sectional elevation of a screw-cutting device embodying the invention. Fig. 2 is a sectional elevation, partly in section, of a portion of the devices shown in Fig. 1, but showing different means for operating these devices. Fig. 3 is a transverse section taken on line 3-3, Fig. 1. Fig. 35 4 is a transverse section on line 4-4, Fig. 2, looking to the left.

Referring now to the drawings, *a*, Fig. 1, indicates a portion of the turret; *b*, a tool-holder mounted in the turret and capable of 40 radial movement therein.

45 *c* indicates a post secured to the turret in axial alignment with the tool-holder *b*, against which certain parts of the screw-cutting device come in contact to effect the closing of the dies by means which will be fully described farther on.

The screw-cutting device proper consists of a solid cylindrical head *d*, having a shank *e* thereon fitting in the tool-holder *b*. This 50 head, which in end view is shown in Fig. 3, is radially slotted to receive the dies *f*, which are held in place in the head by a circular

plate *g*, which is screwed to the end of the head by screws *h*, (shown only in Fig. 3 in section,) it being understood that the dies *f* 55 when in position in the head *d* may slide freely in their radial slots when the plate *g* is screwed down firmly on the head. This plate has a central perforation therein, as shown and indicated by *i*, through which the 60 work may be introduced to the dies, and in line with this opening *i* is a hole *j*, bored in the head and extending down into the shank *e*. A transversely-located perforation *k* extends through the hole *j*.

65 Extending from the bottom of the radial slots in which the dies *f* slide are narrower slots, (indicated by *m*,) which extend through the head *d*, parallel with the axis thereof, in which the levers *n* are mounted pivotally on pins *n'*. The upper ends of these levers enter a notch *o* cut in the under side of the dies, the opposite end of said levers extending down below the head and along the shank *e*, the inner edge thereof having two rectangular steps *p* and *q* cut therein.

70 Sliding on the shank *e* is a collar *r*, whose forward edge may engage the steps *p* and *q* on each of the three levers *n*. When the collar rests on the steps *p*, as shown in Fig. 1, 80 the dies *f* will be moved radially toward the center of the head. When the collar *r* is drawn back on the shank in position to engage the steps *q* of the levers *n*, then the dies *f* will be moved radially away from the center 85 of the head, this movement being effected by a spring *s*, located between the lower end of each lever *n* and the cylindrical shell *t*, which incloses said levers and the parts of the device of the head, this movement being effected by by which the latter are operated. Preferably 90 the lower edge of the head *d* is turned down, as shown, to receive the shell *t*, which may be secured to it in any desired way. Back of the

95 collar *r* is a second sliding collar *u*, which has a sliding fit in the shell *t*, and thus constitutes a closure for the latter, whereby the parts within the shell are protected from dirt and chips. On the inner surface of the collar *u* there is a hub-like projection of smaller diameter than said collar, having a tapered forward end, (indicated by *v*,) so located as to slide under the free ends of the levers *n* when the collar is pushed toward the dies, as by its contact with the post *c*, when the tool-holder is retracted,

and between this collar *u* and the collar *r* is a spiral spring *w*, so arranged as to normally press the collar *r* toward the dies and the collar *u* in the opposite direction. The movement 5 of the collar *r* toward the dies is limited by a cross-head *x*, located in the transverse slot *k* in the shank *e* and passing through the plunger *y*, located in the hole *j*. When the collar *r* is in its most forward position, the steps *p* of the 10 levers *n* will rest on the forward edge thereof.

From the above description it is obvious that the sliding movement of the collar *u* operates only to move the dies inward, and the movement of this collar will compress the 15 spring *w*, and as soon as the tapered end of the collar has swung the inner ends of the levers *n* outward far enough to release the end of the collar *r* from the steps *q* then the spring *w* will shoot the collar forward into a 20 position of engagement with the notches *p*, thus locking the dies *f* in a closed position. If now the tool-holder *b* be advanced toward the work, the spring *w*, operating in inverse direction on the collar *u*, will cause the latter 25 to slide rearwardly, whereby its tapered end may be withdrawn from under the end of the levers *n*, the springs *s* holding the levers *n* firmly against the periphery of the collar *r*. Any suitable stop, as the collar *z*, may be 30 used to limit the rearward movement of the collar *u*. The collar *r* thus serves as a gage to determine the degree to which the dies may be opened. As the dies perform their work 35 on a rod the end of the latter will come in contact with the end of the plunger *y*, forcing the latter and the collar *r* rearwardly until the forward end of the collar reaches the steps *q*, whereupon the springs *s* behind the levers *n* will operate to throw the ends of the 40 latter inwardly and retract the dies *f* from the work, this movement of the levers *n* being permitted by the retirement of the collar *u*. It is thus seen that the function of the collar *u* is to reset the dies and the function of 45 the collar *r* to hold the dies in their operative position, the diameter of said collar *r* serving as a gage to determine accurately the diameter of the work measured from the bottom of the thread cut thereon. I am aware that it 50 is not broadly new to construct a screw-cutting device having radially-movable dies which are set in operative position by means of a cone operating substantially like that on the collar *u*, but it is new, so far as I am aware, 55 to construct a device of this character in which there is embodied a member associated with the cone which serves as an accurate gage to determine the diameter of the work and to positively hold the dies up to 60 their work. Where the cone performs both of these functions, a very slight variation in the movement of the cone will result in a like variation in the diameter of the finished work, and the operation of such a device is too un- 65 certain to permit of its use in cases where it is necessary that the work should be accurately finished.

In the foregoing description that type of the screw-cutting device in which the dies are opened by a longitudinal movement of the device has been described; but, as heretofore explained, the dies may be operated by other mechanism than that just described, consisting of the post *c*, and other means for imparting forward movement to the collar *u* 70 are shown in Figs. 2 and 4, Fig. 2 particularly showing most clearly the modification in the construction of the device whereby endwise motion of the collar is imparted by means of two inclines, (indicated by 2,) which are cut 75 on the rear edge of the collar, and pins 3 in the shank *e* at right angles thereto are so located that if the collar *u* be rotated the action of these inclined planes on said pins will force the collar forward toward the dies during 80 its rotative movement. These inclines start from notches 2^a, located in opposite sides of the collar *u*, in which the ends of the pin 3 rest when the collar is in its normal position. To effect this movement, a short arm 4 is secured to the rear of the collar and projects 85 beyond the casing at right angles to the shank *e*, as shown in said Figs. 2 and 4. On the frame of the machine (indicated by 5) a block 90 95 100 105 110 115 120 125 130 135 140 145 150 155 160 165 170 175 180 185 190 195 200 205 210 215 220 225 230 235 240 245 250 255 260 265 270 sition, and means to slide said second collar toward the first-named collar.

2. A radially-slotted circular head, dies located in the slots in the head, levers pivoted in the head under the dies and parallel with the axis of the head to engage the dies to move them endwise, the inner edge of said levers having steps formed therein; suitable means to swing the free ends of the levers outwardly, and a separate spring-actuated member adapted to snap under the ends of said levers upon their outward movement to engage one of the steps formed on the latter whereby the degree of opening of said dies may be limited, and means actuated by the work to displace said spring-actuated member.

3. A radially-slotted circular head, dies located in the slots in the head, levers pivoted in the head under the dies and parallel with

the axis of the head to engage the dies to move them endwise, the inner edge of said dies having steps formed thereon; suitable means to swing the free ends of the levers outwardly consisting of a collar slidable and rotatable on said head, portions of said collar being spirally disposed thereon; an abutment on the head against which said spiral portions may bear, and means to rotate said collar; a separate spring-actuated member adapted to snap under the ends of said levers upon their outward movement to engage one of the steps formed on the latter, whereby the degree of opening of said dies may be limited, and means actuated by the work to displace said spring-actuated member.

EDWIN W. BULLARD.
